UNITED STATES PATENT OFFICE

2,453,300

LENS GRINDING MACHINE

George E. Bonin, Southbridge, Mass., assignor to
Simonds Machine Co., Inc., Southbridge, Mass.,
a corporation of Massachusetts

Application September 18, 1946, Serial No. 697,701

5 Claims. (Cl. 51—64)

1

This invention relates to a machine for grinding or lapping optical lenses or other similar products having segmental spherical concave or convex surfaces.

It is customary in such machines to provide a lap which is the reciprocal of the desired contour and a work piece which is shaped to the desired contour. The work and lap are then relatively reciprocated under pressure and with a suitable grinding compound until the work is given the reciprocal contour of the lap.

It is the general object of my invention to provide improved mechanism for effecting such relative motions of the work and lap so that a very accurate grinding operation may be more rapidly performed.

To the accomplishment of this general object, I provide means for reciprocating the lap in one direction and means for reciprocating the work in a transverse direction. I also provide means for transversely shifting the locus of the transverse reciprocation, and means for applying any desired pressure to the work during the grinding operation. I also mount the work in such manner that it may be easily released for inspection or replacement.

My invention further relates to arrangements and combinations of parts which will be hereinafter described and more particularly pointed out in the appended claims.

A preferred form of the invention is shown in the drawings, in which

Fig. 1 is a plan view of my improved machine;
Fig. 2 is a side elevation thereof;

Fig. 3 is a front elevation thereof, partly broken away;

Fig. 4 is a front elevation of a gear box forming part of my improved machine; and

Fig. 5 is a left-hand sectional side elevation, taken along the irregular line 5—5 in Fig. 4.

The operating parts of the machine are mounted on a base B (Fig. 2) having a hinged cover C which may be manually lifted and may be supported in raised position by a brace 9.

Referring particularly to Fig. 2, the lens or similar workpiece W is cemented or otherwise secured to a block 10 which is engaged by a pair of pointed studs 12 (Fig. 3) which are clamped in a rocker 14 (Fig. 2) pivoted on studs 16 in depending arms 17 forming part of a work-shifting head 20.

The lower surface of the work W engages a lap which may be concave as shown at L in Fig. 2 or convex as shown at L' in Fig. 3, according to

2

whether a convex or concave reciprocal finished surface is to be produced on the work.

The lap L or L' is mounted on a forwardly projecting portion 22 of a carriage C and may be clamped thereon by a dog 24 (Fig. 2) which may be tightened against the lap by turning a hand wheel 25. The rear portion 30 (Fig. 2) of the carriage C extends through a longitudinal slot 31 in the front wall 32 of the machine casing and the carriage portion 30 is provided with a plurality of rolls 33. The portion 30 is elongated and has a set of the rolls 33 at each end, which rolls engage a fixed guide-bar 35 on the top and bottom surfaces thereof and on the front and rear edges thereof, all as clearly shown in Figs. 2 and 3. The carriage C is thus firmly supported for longitudinal reciprocation during the grinding operation.

Reciprocating motion of the carriage C is produced by a link 40 (Fig. 3) connected at one end to the carriage C and at the other end to a crank arm 42 (Figs. 2 and 3) mounted on a crankshaft 43 rotatable in fixed bearings and provided with a grooved pulley 44. A V belt 45 (Fig. 1) connects the pulley 44 with a driving pulley 46 at the rear of a gear box G shown in detail in Figs. 4 and 5 and to be later described.

In the preferred form of my improved machine, provision is made for grinding two lenses at the same time, and the lap-supporting carriage C is duplicated, as is also the work-supporting and work-shifting mechanism, but a description of one set of these parts will be understood to apply equally to the second set.

Work-shifting mechanism

Each work-supporting head 20 forms a depending part of a shifting member 60 (Fig. 2), to which upper and lower actuating links 61 and 62 are pivoted at 63 and 64. The upper link 62 is of open or yoke form as best shown in Fig. 1 and has eccentric bearings 66 (Fig. 2) on an operating shaft 67. The lower link 62 has a corresponding eccentric bearing 68 on an operating shaft 69. Actuating mechanism to be described rotates the shaft 67 relatively slowly and the shaft 69 at relatively high speed.

The work W is thus given a short rapid forward-and-back motion in rocking engagement with the lap L or L'. The locus of this rapid reciprocation is slowly moved forward and rearward by the upper link 61 which is shifted by the slow-speed eccentric shaft 67.

At the same time the carriage C is being shifted longitudinally of the guide-bar 35 (or traversely

relative to the work) so that the combined effect is to move the work W over the lap L or L' in a constantly shifting path.

Driving mechanism

The various moving parts of my improved machine are actuated from a single motor M (Fig. 1) by means of a V-belt 10 connecting a driving pulley 11 on the motor armature shaft 12 to a driven pulley 13 mounted on the front of the gear box G. Double pulleys may be provided if desired, so that the speed relation between the motor M and the mechanism in the gear box G may be increased or decreased.

The pulley 13 (Fig. 2) is mounted on a shaft 16 supported in bearings at the front of the gear box G. The shaft 16 is connected by a pinion 17, idle gear 18 and gear 19 to the fast eccentric shaft 69. The shaft 69 is connected by a worm 80 (Figs. 4 and 5), worm gear 81, worm shaft 82, worm 83 and worm gear 84 to the slow-speed eccentric shaft 67.

A second worm 86 (Fig. 4) on the shaft 69 engages a worm gear 88 mounted on a shaft 89 which supports the driving pulley 46 previously described and through which the carriage C is reciprocated.

The desired motions and speed relations are thus provided for the longitudinal reciprocation of the carriage C for the rapid transverse reciprocation of the work on the lap, and for the slow shifting of the locus of the rapid reciprocation.

Special provision is made for varying the pressure of the work on the lap. For this purpose, a rod 90 (Fig. 2) for each grinding unit is connected at 91 to arms 92 mounted on a shaft S pivoted above the gear box G. The lower end of each rod 90 extends freely through a bearing in a stud 93 mounted in depending lugs 93a on the associated link 61. A nut 94 is threaded on the upper part of the rod 90 and a spring 95 is interposed between the nut 94 and a washer 96 which engages the stud 93. A collar 97 is fast on the lower end of the rod 90. Arms 100 (Figs. 2 and 3) are attached to each shaft S and each arm 100 has a holding latch 101. By unlatching and swinging the arms 100 forward, the collars 97 may be drawn back against the studs 93. Further movement raises the work-actuating structure.

Downward pressure is thus applied by the spring 95 to the outer or swinging end of the link 61 and this pressure is communicated through connecting parts to the work W. The pressure may be varied by adjusting the nut 94 on the threaded rod 90.

Having thus described my invention and the advantages thereof, I do not wish to be limited to the details herein disclosed, otherwise than as set forth in the claims, but what I claim is:

1. In a lens grinding machine having a work-engaging member and a lap, in combination, a carriage for said lap, a guide-bar, means to reciprocate said carriage along said guide-bar, a depending work-actuating member mounted on

upper and lower shiftable pivots, and means to give the work a compound transverse reciprocating movement by moving one of said pivots to rapidly reciprocate said work transversely of the path of movement of the lap and by moving the other pivot to slowly shift the locus of the path of reciprocating movement of the work during such rapid reciprocation transversely of said path of movement of the lap while maintaining the length of said transverse reciprocating movements substantially constant.

2. In a lens grinding machine having a work-actuating member and a lap, in combination, a carriage for said lap, a guide-bar, means to reciprocate said carriage along said guide-bar, a depending work-actuating member mounted on upper and lower shiftable pivots, a pair of links pivoted at vertically spaced points to said work-actuating member, eccentric bearings for the other ends of said links, and means to give said work-actuating member a compound transverse reciprocating movement by rotating one eccentric relatively rapidly and the other eccentric relatively slowly.

3. The combination in a lens grinding machine as set forth in claim 2, in which a spring applies downward pressure to the work-actuating member and work, and in which means is provided to vary the operative effect of said spring.

4. The combination in a lens grinding machine as set forth in claim 2, in which a spring applies downward pressure to the work-actuating member and work, and in which means is provided to release said spring pressure and to raise said work-actuating member out of operating position.

5. In a lens grinding machine having a lap, in combination, a work-actuating member, parallel links supporting said member and pivoted to said member at upper and intermediate points, means to reciprocate one link endwise relatively rapidly to shift the work transversely of the lap, means to reciprocate the other link endwise relatively slowly to shift the locus of the path of reciprocating movement of the work during such rapid transverse reciprocation while maintaining the length of said transverse reciprocation substantially constant, and means to apply controlled downward pressure to said actuating member.

GEORGE E. BONIN.
